DAVID S. JACOBUS, OF MONTCLAIR, NEW JERSEY, ASSIGNOR TO THE BABCOCK & WILCOX COMPANY, OF BAYONNE, NEW JERSEY, A CORPORATION OF NEW JERSEY

FURNACE WALL AND BAFFLE

Original application filed November 27, 1925, Serial No. 71,517. Divided and this application filed May 7, 1929. Serial No. 361,154.

This is a division of my copending application Serial No. 71,517, filed November 27, 1925.

This invention relates to tile for making baffles especially useful in connection with water tube boilers, and will be understood from the description in connection with the accompanying drawings, in which Fig. 1 is a side elevation illustrating an embodiment of the invention; Fig. 2 is a section along the line 2—2 of Fig. 1; Fig. 3 is a section taken on the line 3—3 of Fig. 1; Fig. 4 is a view, similar to Fig. 3, of a modification; Fig. 5 is a section along the line 5—5 of Fig. 4; Fig. 6 is a section through a boiler on a small scale, showing how the baffles may be located.

In the drawings, reference character 10 indicates water tubes of a water tube boiler between which the tile may be installed for the purpose of providing a baffle for the hot gases. A tile made in accordance with my invention is illustrated at 11, and consists of a block having opposite sides parallel, and its front and rear faces in the shape of a non-rectangular parallelogram. Its ends are hollowed out or made concave, so that they will fit the outside surfaces of the tubes 10 between which they are installed, it being observed that these opposite ends are offset with respect to each other in a direction longitudinal of the tubes. In installing the same, as shown in Fig. 1, the bottom tile 11' is made with a surface that will adapt it to fit flat against the header 15, and each one of the successive tiles is installed thereabove by introducing the same while held in a vertical position between the tubes, and then turning the same anticlockwise, as seen in Fig. 1, until the rounded ends come into contact with the tubes, after which it is permitted to slide downwardly into contact with a lower tile, and the tubes hold the same in place. One of the rounded end portions of the bottom tile 11' is curved at 11" to enable it to be turned into place. The angle of slope of the top and bottom edge surfaces of the tile 11 with respect to the rounded ends thereof is such that the point 12, where the top edge of one of the rounded ends contacts with one of the tubes, and the point 13 where the lower

edge of the other rounded end contacts with the other tube, will be substantially horizontal so that the point 12 will serve as a pivot around which the tile 11 can be swung upwardly to remove the same. The tile when in place between the tubes fits the tubes closely from top to bottom on each side.

When the usual form of tile with horizontal joints is used, it is impossible to form the tile so that they will fit in the desired manner against the tubes from top to bottom, because after turning the tile into place there will be a line contact instead of a contact of a considerable portion of the entire surface at each side of the tile. It can therefore be seen that by making the joints which come at the top and bottom of the tile at an angle with the horizontal a tile may be used which will contact with the tubes from top to bottom, and thereby provide a much better thermal contact with the tubes and a tighter joint to prevent gas leakage than can be obtained with a tile having horizontal joints. It will thus be seen that the tile can be readily installed and removed, and will be securely retained in position by the tubes 10 when they are in place to form with the tubes a baffle. It will be understood that other tile will be similarly installed in the spaces between rows of tubes to form a baffle of the desired width, and a sufficient number of tile will be installed to make the baffle the desired length.

In the modification shown in Figs. 4 and 5, the middle portion of the tile 16 is made narrower, thus making the tile less bulky while still retaining the advantages of ease of installation and removal, and security of position when installed. In this modification, tile are shown with grooves 17 along their top surfaces and corresponding ribs 18 along their lower surfaces, as most clearly shown in Fig. 5, so that the danger of escape of radiant heat or gases between the tile is obviated.

The tile may be installed, for example, between rows of tubes as shown in Fig. 6, in which 19 and 20 indicate the steam and water drums of a boiler of the Stirling type connected by banks of tubes with the mud drum 21, the tile being installed between rows of

such tubes to provide baffles which will cause the gases to be deflected, as indicated by the arrows in this figure.

I claim:—

1. A wall member adapted to be placed between fixed cylindrical surfaces, having one of its sides rounded to fit one of said surfaces and having its opposite side rounded to fit another of said surfaces, and having two of its other sides parallel to each other and making angles other than right angles with its rounded sides and perpendicular to a common plane.
2. A wall member adapted to be placed between fixed cylindrical surfaces, having one of its sides rounded to fit one of said surfaces and having its opposite side rounded to fit another of said surfaces, and having two of its other sides forming acute angles with its rounded sides and parallel with each other, and also having the remaining sides parallel with each other.
3. A baffle comprising two adjacent tubes substantially parallel to each other and a plurality of blocks disposed between said tubes, each block having oppositely disposed cylindrical surfaces adapted to engage said tubes, and oppositely disposed faces extending between the cylindrical surfaces and forming part of the opposite faces of the baffle, each of said faces being substantially in the form of a non-rectangular parallelogram.
4. A baffle comprising two adjacent tubes substantially parallel to each other and a plurality of blocks disposed between said tubes, each block having oppositely disposed cylindrical surfaces adapted to engage said tubes, one of said surfaces being offset longitudinally of the tubes with respect to the other.
5. A baffle comprising two adjacent tubes substantially parallel to each other and a plurality of blocks disposed between said tubes, each block having oppositely disposed cylindrical surfaces adapted to engage said tubes, and two substantially parallel edge surfaces extending between said cylindrical surfaces and adapted to contact with corresponding edge surfaces on adjacent blocks in the baffle, each of said two edge surfaces forming acute angles with the axes of said tubes.

DAVID S. JACOBUS.
